LIQUID VENDING APPARATUS

Robert R. Hull, Pasadena, Calif., assignor, by
mesne assignments, to California Fruit Growers
Exchange, Los Angeles, Calif., a corporation of
California

Application May 20, 1947, Serial No. 749,246

28 Claims. (Cl. 225—21)

1

This invention relates to Liquid Vending Apparatus; and it relates more particularly to an apparatus of the type suitable for vending a consumer unit volume of potable beverage into a cup from a relatively large supply of such beverage, all of the operations involved being effected automatically after actuation by a customer of suitable control mechanism incorporated in the apparatus.

Applicant has previously disclosed in his co-pending application, Ser. No. 641,267, filed January 15, 1946, an apparatus for vending suitable portions of a beverage to a consumer, and it is a purpose of the present invention to adapt such apparatus for completely automatic operation.

The apparatus herein disclosed is especially adapted to store in bulk a volume of beverage, for example, orange, tomato, pineapple, apple or other fruit or vegetable juice, more desirably in refrigerated condition, and to effect a withdrawal therefrom of an exactly predetermined volume of appropriate amount for a single drink, such withdrawal being accomplished automatically upon the insertion of a coin in the machine by the customer. It is also an object to provide means for returning the customer's money to him should the supply of beverage be insufficient to enable the apparatus to dispense the proper amount of beverage. It is a particular feature of this invention, therefore, to combine with such vending means heretofore disclosed, suitable means for preventing further dispensing action of the apparatus after the supply of beverage has been reduced to a point where a full portion can no longer be dispensed. In this instance, this is accomplished by weighing the amount of beverage being dispensed and by utilizing this weight to control the further operation of the machine.

In general, the present invention consists of a dispensing unit which includes a refrigerated compartment and a power actuated dipper or scoop pivotally mounted within this compartment to depend into a beverage supply tank and capable of being oscillated therein to effect agitation of the beverage. Moreover, this dipper is adapted and arranged to be swung, upon demand, to a point beyond its normal limit of oscillatory movement to withdraw a portion of the beverage contained in the tank. An automatic cup dispensing mechanism is also included for supplying a paper cup to which the beverage portion withdrawn may be delivered. Suitable power means and associated transmission are provided for accomplishing the foregoing operations, as well as coin-actuated electrical control

2

means for properly coordinating these operations in timed sequential relation. Refrigeration may also be incorporated, if desired, to maintain the beverage in a more potable condition.

5 Further objects of the invention will appear in connection with the description of the invention illustrated in the accompanying drawings in which

Fig. 1 is a view in elevational perspective of 10 the assembled apparatus;

Fig. 2 is a view in front elevation of Fig. 1, in 15 which the outer cabinet door has been swung open to expose certain parts of the inner assembly;

Fig. 3 is a fragmentary view of the inner assembly in which the front panel of the refrigerated compartment has been opened to permit access to the supply tank and dispensing dipper;

Fig. 4 is a top plan view of the inner assembly 20 with the outer cabinet removed;

Fig. 5 is a partial view in rear elevation showing the driving motor and parts of the dipper actuating mechanism;

Fig. 6 is a sectional view on line 6—6 of Fig. 5 25 of a transmission assembly;

Fig. 7 is a view looking in the direction of the arrows on line 7—7 of Fig. 4 showing the arrangement of certain electrical control apparatus;

Fig. 8 is a detailed view of the dipper in its operating position within the refrigerated compartment, showing a part of its supporting and actuating assembly and associated discharge nozzle;

Fig. 9 is a schematic diagram of an electrical circuit suitable for controlling the automatic operations of the apparatus.

In the particularly desirable embodiment of the apparatus here shown, a removable outer cabinet 20 is provided for enclosing the dispensing unit assembly, indicated generally in the drawings at A. As shown in Figs. 1 and 2, cabinet 20 is provided with interlocking front and side panels 21 and 22, respectively, suitably hinged to the cabinet to permit them to be unlocked and swung open to gain access to assembly A or for removal of the latter entirely from the cabinet, if desired. Cabinet 20 serves to prevent tampering with the enclosed operating mechanism and provides sanitary protection therefor, as well as giving the whole assemblage a pleasing external appearance. A refrigerating unit, if employed, may be located in the lower part of the cabinet and ventilating apertures 23 in the cabinet are provided to permit proper circulation of air. Similarly, screened louvres 24 at the upper sides 55 of the cabinet permit ventilation of assembly A.

A cup access aperture 25 is cut in the central portion of panel 21 to permit removal of the cup by the customer at the completion of the vending operation, and a window 25a just above this aperture permits the customer to see when the flow of beverage to the cup has stopped. In addition, door panel 21 is provided with a coin-receiving slot 26 and subadjacent guide 27 for delivering a deposited coin to coin mechanism 28. A receiver 29 for coins refused by the machine is also secured to this panel. Guide 27 and receiver 29 are so positioned on panel 21 as to bring them into proper alignment with coin mechanism 28 whenever the panel is in its closed position. An aperture 30 in panel 21 permits access by the customer to receiver 29 to enable him to recover returned coins. A "reject" knob 1, also carried by panel 21, projects therethrough and is actuated by the customer to recover coins which are bent or for other reasons stick within the coin mechanism. Knob 31 is likewise so positioned on panel 21 as to cause it to come into proper alignment with its associated coin mechanism 28 when panel 21 is closed.

The actual drink-dispensing device here employed is similar to that described in applicant's aforementioned copending application. In this instance, this device comprises that part of assembly A, shown more particularly in Figs. 3 and 8, which is centrally disposed of the apparatus. It consists essentially of a beverage supply tank 32 within a refrigerated compartment 33, and a hollow-handled dipper 34 pivotally suspended from the roof or upper partition 35 of compartment 33 to hang downwardly into tank 32. A horizontal shaft 36 projects through the rear wall 37 of the compartment and is journaled in suitable bearings 38 within a housing 38a which is supported from upper partition 35. Shaft 36 is provided with a drive sprocket 39 at its outer end and with suitable bayonet joint engaging-pins 40 at its inner end. This inner end is adapted to engage and support dipper 34 as well as impart the various necessary swinging motions to it. For this purpose, the handle of the dipper is constructed in the shape of a T at its upper end, its hollow stem 41 being bent at right angles to form an elbow 42 completing one arm of the T while a sleeve 43 is welded on at the bend so as to be concentrically aligned with the terminal portion of elbow 42 and thus form the other arm of the T. Sleeve 43 is provided with a conventional bayonet socket at its free end by which it is adapted to receive and engage the inner end of shaft 36 and pins 40 thereof. A spring 44 is interposed between the end of shaft 36 and the base of the socket in sleeve 43 to ensure a positive locking engagement between the shaft and the dipper. By means to be described in detail hereinafter, dipper 34 is normally actuated by shaft 36 to oscillate back and forth in tank 32 within relatively small angular limits and thus impart an agitating effect to the beverage contained therein. This not only assists in maintaining the beverage in chilled condition but is particularly advantageous in connection with such beverages as orange or tomato juice where it is very desirable to keep the solid matter of such juices uniformly suspended throughout the entire volume. When, however, it is desired to dispense a drink from supply tank 32, dipper 34 is swung to cause it to scoop up a volume of beverage in its scoop end and, as the swing is continued beyond the forward limiting position of an agitat-

ing cycle, to lift the scoop above the level of elbow 42. As this occurs, the beverage will, of course, flow from the scoop through the hollow handle 41 and thus be discharged at the open end of the elbow. From this point, the beverage is conducted to a receiving cup or container by a discharge spout or nozzle 45. This nozzle projects through an aperture 46 in front panel 47 of the refrigerated compartment and is detachably secured therein by flange 45a which is slipped under a spring clip 45b on panel 47 by rotative movement of the nozzle within aperture 46. The terminal portion of elbow 42 telescopes within the inwardly extending shank of nozzle 45, the shank being made sufficiently long and of suitable internal diameter for this purpose. Since nozzle 45 is fixed in panel 47, the swinging action of dipper 34 causes relative angular movement to occur between adjacent surfaces of elbow 42 and the nozzle. In order to eliminate any bearing surface at this point with which the beverage might come in contact and thus become contaminated, the internal diameter of the nozzle shank is made appreciably greater than the external diameter of elbow 42 so that no contact can occur between adjacent portions of the shank and the elbow. This arrangement, moreover, facilitates the opening of panel 47 without the necessity of first removing nozzle 45. A platform 48 is provided below nozzle 45 for supporting a cup during the dispensing operation.

An automatic cup dispenser 49 is included in assembly A, and the subadjacent guards 49a, secured to panel 47, serve to guide a cup to its proper position on platform 48 below nozzle 45. This dispenser is electrically controlled and is adapted and arranged to deliver a cup each time a coin is deposited in the machine. Further detailed description of the operation of this dispenser will be given in connection with the electrical system diagram.

In order to provide easy access to the supply tank 32 for refilling purposes, panel 47 is hinged along a vertical edge to assembly A to permit it to be swung open, as shown more particularly in Fig. 3. Suitable spring closure means 47a is provided along the free edge of panel 47 to enable the panel to be securely retained in the closed position during operation of the apparatus. Thus, in order to refill tank 32, it is merely necessary to release closure means 47a to open panel 47, sufficient clearance being provided between elbow 42 and discharge nozzle 45 to permit this without first removing nozzle 45. In this instance, tank 32 is provided with an arcuate shaped well 32a in its bottom into which dipper 34 is adapted to swing. The purpose of the well is to cause the remaining beverage to collect at this point as the supply diminishes so that as much as possible of the original beverage may be removed before refilling becomes necessary. Because the well causes tank 32 to have an irregularly shaped bottom, the tank is more readily supported within the compartment 33 by means of flange-engaging lips 32b along the upper opposite ends of the tank. Flanges 32c are secured to opposite side-walls of the compartment for supporting the tank by these lips. By swinging the dipper to the position shown in Fig. 3 so that it clears well 32a, the tank may then be slid forward along its supporting rail 32c a sufficient distance to make it accessible for refilling. If it is desired to remove the tank entirely, this may be done by first raising dipper 34 to its highest or dispensing position where it

will thus clear the upper edges of the tank as the latter is withdrawn. It is also possible, of course, to remove the dipper itself, if desired, by pressing inwardly in the direction of shaft 36 and then turning to disengage it from the shaft at the bayonet joint.

Power for effecting the agitating or dispensing action of the dipper is supplied by a motor M through a power transmission B, both of which are mounted on the top of unit A.

Oscillatory motion is imparted to the dipper to agitate the beverage within the supply tank by means of transmission B through a horizontal driven shaft 50 and a plate crank 51 made fast with the outer end of this shaft for rotation in a vertical plane. Plate crank 51 is provided with a crank pin 51a which is secured near the periphery of the crank. Connection between pin 51a of the plate crank and drive sprocket 39 on dipper actuating shaft 36 is made by a roller-chain and spring assembly, as shown more particularly in Fig. 5. A central section of roller chain 52 of this assembly passes around and operatively engages sprocket 39. One end of chain 52 is fastened to the lower end of spring 53, while its opposite end is fastened to the lower end of a second spring 54. Roller-chain 55 connects the crank pin 51a of plate crank 51 to the upper end of spring 53 where it is secured by an attaching bracket 53a. Spring 54 is fastened at its upper end to the rear wall 56 of assembly A by means of a tension adjusting screw and bracket assembly 57.

Plate crank 51 is driven continuously while motor M is in operation and therefore during 180° of rotation will cause chain 52 to be pulled over sprocket 39 in a clockwise direction (Fig. 5) against the tension of spring 54. As the plate crank completes the other 180° of rotation, the tension set up in spring 54 will then cause chain 52 to be pulled back over sprocket 39 in the reverse direction as crank pin 51a returns to its lowest position. In this manner a continuous oscillatory motion is imparted to the dipper. For reasons to be described presently, the tensile strength of spring 53 is so proportioned to that of spring 54 that no appreciable extension of the former takes place during the above described cycle of operation.

In order to effect the desired dispensing operation, transmission B is provided with a second plate crank 58 which is secured to the outer end of a horizontal shaft 59, parallel to shaft 50 so as to be rotatable in the same plane as crank 51. A crank pin 60 projects through a hole 58a (Fig. 7) in plate crank 58 and is secured to a cam plate 61 which is pivotally mounted on the inner face of the plate crank. A short chain segment 62 connects this crank to the upper end of spring 53 by means of bracket 53a where it forms a Y junction with chain 55. The diameter of crank 58 is substantially greater than that of crank 51 so that when this plate is rotated it will cause a greater linear movement of chain 52 and thus turn sprocket 39 through a larger angle than does crank 51. Plate crank 58 is normally idle, but, by means of a solenoid controlled clutch, may be connected to the power source to cause the crank to rotate.

In the particular position shown in Fig. 5, crank pins 51a and 60 of cranks 51 and 58, respectively, are at the minimum or starting positions of their respective crank throws. In this condition, dipper 34 is held in its most rearward position (i. e., to the right in Fig. 5) by the ten-

sion of spring 54 acting through chain 52 and sprocket 39. Because the diameter of crank 58 is greater than that of crank 51, rotation of the former (in a counterclockwise direction as here shown) overcomes the effect of the latter and thus chain 55 simply becomes slack and has no effect upon dipper 34, although crank 51 continues to rotate. As pin 60 nears the top of its throw, dipper 34 has been swung upwardly far enough to bring its scoop end above the level of elbow 42. Continued rotation of crank 58 would normally, of course, cause dipper 34 to be swung still farther until pin 60 reached the top of its throw, after which it would again begin its descent. It has been found desirable, however, to stop the swing of the dipper at a point just slightly above the horizontal plane of its axis and to hold it there momentarily to permit the beverage contained in the scoop to drain out completely. In order to accomplish this purpose, sprocket 39 is provided on its inner face with a pin 63 which is adapted to engage an adjustable stop 64 secured to the rear wall 56 of assembly A, as shown in Fig. 7. The abutment of pin 63 against plate 64 (indicated here in broken lines) is set to occur before pin 60 has reached the top of its throw. Because sprocket 39 is thus prevented from turning any farther, continued rotation of plate crank 58 causes spring 53 to be stretched while crank pin 60 passes through the upper portion of its path of movement. During this period, of course, there will be no movement of dipper 34, but as pin 60 returns toward its minimum position, spring 53 once again assumes its original condition and subsequent travel of pin 60 will then permit spring 54 to return dipper 34 to its rearmost position as previously described. After plate crank 58 has made one complete revolution, it is automatically disconnected from its power source and remains idle until another vending operation is desired. The control of dipper 34 is thereby returned to plate crank 51 and the normal agitating cycle is resumed.

As previously mentioned, power is supplied to rotate plate cranks 51 and 58 by motor M which is connected through coupling 65 to drive shaft 66 of transmission B. Shaft 66 is suitably journaled in the transmission housing 67 and has a worm gear 68 pinned thereto which meshes into gear 69 fixed on shaft 70. Shaft 70 extends at right angles to shaft 66 and is provided at its ends with suitable bearings 71, 72, in gear case 67. A pinion 73, also fast on shaft 70, meshes into a spur gear 74 secured to shaft 50. Shaft 50 is parallel to shaft 70 and is provided with bearings 75, 76, in the gear case. As mentioned above, agitating plate crank 51 is mounted on the outer end of shaft 50 outside the gear case and is caused to rotate continuously by motion transmitted through the gear train just described whenever motor M is in operation. A pinion 77 is secured to shaft 50 within the gear case and meshes with a spur gear 78 which is freely rotatable on shaft 59. Bearings 79, 80, in gear case 67 are provided for shaft 59, and vending or dispensing plate crank 58 is secured to the outer end of this shaft. In order to impart rotation to shaft 59, a pin-clutch assembly C is secured on shaft 59 adjacent gear 78 and is adapted and arranged to engage this gear. Engagement between clutch C and gear 78 is accomplished in this instance by holes 81, 81a, in the web of gear 78 which are adapted to receive a sliding pin 82 of the clutch. For this purpose, pin 82 is mounted upon a carrier plate 83 which is axially slidable on shaft

59, whereby it can be moved toward or away from gear 78 to effect engagement or disengagement of the pin with hole 81 or 81a of the gear. A clutch driving collar 84, also secured to shaft 59, is placed intermediate carrier plate 83 and gear 78 and has a hole 85 through which pin 82 projects and by which it is slidably engaged. A second pin 86, diametrically opposite pin 82, is also mounted on carrier plate 83 and slidably engages collar 84 in hole 87. This pin is provided only to assist in guiding pin 82 and for this reason is made much shorter than pin 82 to prevent its projecting completely through collar 84 when the clutch is fully engaged. Springs 88, through which pins 82 and 86 pass, bear against collar 84 and carrier plate 83 at their opposite ends, respectively, and yieldingly hold the clutch in its disengaged position. For engaging gear 78, a clutch arm 89 contacts carrier 83 and forces it toward collar 84 until the longer pin 82 strikes the web of gear 78. As gear 78 rotates continuously, one of the holes 81 or 81a will eventually come into alignment with pin 82 and the pin will then be inserted into it by the further action of clutch arm 89. Once pin 82 has been projected into one of its cooperating holes in gear 78, the motion of the gear is then transmitted to shaft 59 and accordingly to the vending plate crank 58.

Clutch arm 89 is secured to the inner end of a shaft 90 which extends transversely to shaft 59 and projects through the end wall of transmission B. Bearings 91, 92, in housing 67 support the shaft to permit rotation of arm 89 while collars 93, 94, which are secured on shaft 90, bear against bearings 91, 92, respectively, to retain the shaft against longitudinal movement. A lever 95 is secured to the outer end of shaft 90, and a clutch actuating solenoid connects to this lever. In this instance, the clutch is controlled by solenoid 96, as shown in Fig. 5, which is mounted on a bracket 97 above the clutch lever. An armature 98 is coupled to lever 95 by means of a spring 99. The actuation of this solenoid causes armature 98 to be withdrawn upwardly into the solenoid and this motion is transmitted through spring 99 to lever 95. Spring 99 allows armature 98 to complete its travel while at the same time the travel of lever 95 and clutch arm 89 may not be completed if pin 82 does not happen to align with one of the holes 81, 81a, in gear 78 at that moment. When such alignment is effected, however, by the rotation of gear 78, tension in spring 99 is sufficient to overcome that of springs 88 and cause pin 82 to be forced into either hole 81 or 81a. It can be seen, therefore, that spring 99 must be fairly stiff to ensure positive action of the clutch, and consequently solenoid 96 must be capable of overcoming a rather heavy pull. In order to reduce the size of the solenoid necessary to effect this operation, the linkage between the clutch lever 95 and armature 98 is made sufficiently loose in the deenergized condition of the solenoid so that no stretching of spring 99 occurs until armature 98 has moved an appreciable distance. In this manner, the armature can acquire enough momentum before any stretching of the spring takes place to make it practical to use a much smaller solenoid than would be possible if the armature started its travel under spring tension.

Upon the completion of one revolution of plate crank 58, the solenoid is deenergized, tension is removed from spring 99, and springs 88 immediately withdraw pin 82 from engagement with gear 78, thus disconnecting the plate crank from

its source of power. Operation of the solenoid to establish the driving connection just outlined is controlled by an electrical circuit described hereinafter.

It is desirable for various reasons, though not indispensable to the satisfactory operation of the apparatus, to have the start of a dispensing cycle occur at certain positions of the dipper during its agitating cycle. It becomes increasingly more difficult, for example, to obtain uniform measured quantities of the beverage for every dispensing operation if the vending cycle is begun when the dipper is in that portion of its agitating cycle in which it is moving away from the dispensing position. At such a time, the direction of movement of the dipper would, of course, be suddenly reversed and this is likely to cause at least some of the beverage contained in the scoop to spill out. The greatest uniformity of operation is found to obtain when the vending cycle is begun at that point during the agitating cycle in which the dipper is at its rearmost position (i. e. the position farthest from the ultimate dispensing position). This is accomplished by initially securing clutch C on shaft 59 so that clutch pin 82 aligns with hole 81 in gear 78 when the agitating plate crank 51 is at the bottom of its throw and vending plate crank 58 is slightly ahead of the lowest position of its crank throw. Since, in this instance, gear 78 is made to have a diameter twice that of its driving pinion 77, the latter makes two revolutions for every one of gear 78, and accordingly, by spacing a second hole 81a diametrically opposite hole 81 in gear 78, the same timed actuation of the vending crank with respect to the position of dipper 34 will be obtained when engagement of gear 78 is made by this second hole. In this way a full, uninterrupted swing of dipper 34 to its dispensing position will result each time the vending plate crank 58 is caused to rotate, whether clutch C engages gear 78 by hole 81 or 81a. If neither of these holes is aligned with the clutch pin at the time the clutch is initially actuated, the pin will, of course, merely abut against the web of gear 78 and remain there until one of the holes comes into alignment. While it is possible to have the vending crank pin 60 begin its throw at the lowest point in its path of rotation, quicker actuation of the dipper by the vending crank and smoother overall operation is obtained by advancing the pin slightly beyond this lowest point, about 15°, as mentioned above, being effective for this purpose.

The foregoing provisions are designed to ensure the uniformity of the unit volume of beverage dispensed where the supply tank contains enough beverage to completely fill the dipper. Most desirably the apparatus of the invention further includes provision whereby, in order to guard against "short-changing" the customer, the dispensing mechanism is automatically rendered inoperative when the supply of beverage in the tank has become so depleted that the dipper can scoop up and carry with it into dispensing position only a quantity that is not negligibly less than that which the customer is supposed to get for the coin he deposits; provision being also made for rejecting and returning to the customer a coin deposited while this condition prevails. The provision for rendering the dispensing mechanism "inoperative" may be broadly characterized as responsive to the quantity of liquid contained in the dipper or other measuring member while moving into or approaching

dispensing position, and as operable in case of a predetermined deficiency in such quantity to render the dispensing cycle driving means incapable of functioning until normal conditions of beverage supply are restored. For various reasons it is generally desirable in practice that said provision be of such character that it does not render the dispensing mechanism inoperative immediately upon occurrence of the quantity deficiency, but only after a delay permitting performance of, say, one or two more dispensing cycles before shut-down.

Within the broad scope of the invention, it is feasible to employ any of various different specific forms of quantity-responsive means for the purpose indicated. Thus, a change from normal in either the volume (liquid level) or the weight of the portion of beverage in the dipper, removed from the supply in the tank and elevated into dispensing position, may be the quantitative control factor utilized. However, in the specific embodiment herein illustrated by way of example and found to have great practical advantages, the weight factor is utilized. Specifically, provision is made to weigh the dipper and its contents during that part of each dispensing cycle just before the stem 41 of the dipper attains the horizontal in its upward swing; and, when there is a weight deficiency, to utilize this for actuation of circuit control means which operates, in the present instance, to initiate step-by-step changes in the control circuit which result, after only a very few more dispensing cycles have been performed, in preventing energization of the clutch-operating solenoid 95 and hence stop further vending operation of the apparatus.

As here shown (Figs. 7 and 9), a movable cam plate 61, mounted on the rear face of vending crank 58, acts as a weighing arm or lever, displacement of which from normal by a significant weight deficiency in a given dipper load actuates a control switch 105 to initiate the clutch-actuating circuit changes. Cam plate 61 is generally triangular in shape and is pivotally attached at one of its apexes by means of a stud 100 to crank 58 near the periphery thereof. Crank pin 60 is secured to an adjacent apex of the cam and, as previously explained, projects forwardly through an aperture 58a in crank plate 58. Aperture 58a and crank pin 60 are approximately diametrically opposed to stud 100 on the plate crank. In this instance, aperture 58a is about one-half inch in diameter while pin 60 has a diameter of about one-quarter inch with the result that cam plate 61 is thus capable of pivoting about stud 100 within the limits of movement permitted by pin 60 in aperture 58a. The third apex of cam 61 is formed to provide a cam surface having a small lobe 101 which may be moved toward or away from shaft 59 by the pivotal movements of the cam just described.

The cam plate is urged to its most outwardly pivoted position by the action of a spring 103 which is held in compression between a lug 102 on the cam plate and a similar lug 104 fast with the inner face of plate crank 58. This arrangement of parts is designed to permit the greatest radial movement of lobe 101 with respect to plate crank 58. In addition, the arrangement is such that the longest spring capable of fitting within the space limitations present may be used in order to obtain a maximum change of position of the cam plate for any given differential in weight between successive dipperfuls of beverage.

A sensitive type switch 105, of which the well 75

known "Microswitch" is an example, having an actuating arm and cam follower 106, is positioned by means of a suitable supporting bracket on gear case 67 to place its cam follower in the path of rotation of cam 61 where it may be actuated by contact with lobe 101 thereof. As will be described in detail hereinafter, actuation of this switch under certain conditions may cause the machine to cease further vending operations.

As plate crank 58 is rotated in a clockwise direction (Fig. 7), cam lobe 101 of the cam plate will pass under cam follower 106. During this period of rotation of the plate crank, the weight of dipper 34 and its contents is transmitted through the various coupling components to chain 62 and crank pin 60. This weight tends to counteract spring 103, as previously explained, and thus cause cam plate 61, and accordingly its lobe 101, to be retracted toward shaft 59. The positioning of switch 105 circumferentially of plate crank 58 is arranged to cause its cam follower 106 to be engaged by lobe 101, if such engagement occurs at all, when the dipper handle 41 is just below the horizontal in its upward swing. Since the dipper will have its greatest leverage at this point, the effect of variations in the amount of beverage contained is then most pronounced and the best accuracy in the weighing operation is thus obtained. By properly proportioning or adjusting the compression of spring 103, the weight necessary to cause cam plate 61 to pivot a distance sufficient to prevent actuation of switch 105 can be closely controlled. Further control is provided by making the radial distance of switch 105 from shaft 59 accurately adjustable, securing means being provided to retain the switch in position on the supporting bracket once it has been properly adjusted. It will be apparent from the foregoing that the proper setting of the switch is obtained when contact between its cam follower 106 and cam lobe 101 is just sufficient to actuate the switch with cam plate 61 in the most outwardly projected position which corresponds to the predetermined allowable minimum weight of beverage to be dispensed by the dipper. Thus, if the weight of beverage contained is sufficient to cause cam plate 61 to retract slightly toward shaft 59 from the aforesaid position, actuation of switch 105 will not occur and the normal operation of the machine will not be affected.

In addition to switch 105, which may be termed the "weight" switch, two additional switches, 107 and 108, here called the "cycle" switch and "reset" switch, respectively, are employed to assist in controlling the operation of the dipper. These are provided to give the step-by-step or delay action, hereinabove referred to, in rendering the dispensing mechanism inoperative by a customer. Each of these switches is similar in type to switch 105 and is provided with an actuating arm and cam follower 109, 110, respectively. Switches 107 and 108 are supported by brackets from transmission B and are so positioned as to bring their respective cam followers into the plane of rotation of crank plate 58, being placed on either side and slightly forward of switch 105 for this purpose. Switches 107 and 108 are actuated by the passage of cam lobe 58b of plate crank 58 as it passes under the respective cam followers.

The foregoing arrangement of switches is such that they are disposed in an arc of approximately 90° about the periphery of plate crank 58. As seen in Figs. 5 and 7, where cam 58b of plate crank 58 is in contact with cam follower 109 of cycle switch 107, rotation of the crank causes cam 58b

11

to pass completely under and out of contact with cam followers 109 and 110 of switches 107, 108, respectively, before cam lobe 101 of cam plate 61 contacts cam follower 106 of weight switch 105. For this reason, the positioning of cam plate 61 on plate crank 58 must be such as to cause lobe 101 to follow lobe 58b by something more than 90°. In the present instance an angular distance of 105° has been found to be satisfactory. Thus, the operation of the switches is seriatim only, no two switches being operated at the same time. Further detailed description of the function of these switches is given in connection with the electrical system diagram.

The operations of the various components of the apparatus are coordinated through a system of electrical relays 111, 112, 113 and 114 (Fig. 9). These relays are mounted on a removable panel 115 positioned on top of assembly A and slightly to the rear of the cup dispenser 49 (as indicated in Fig. 4). Suitable cabled conductors serve to connect these relays to the various components of the electrical system.

Referring to Fig. 9, a particularly desirable form of electrical control circuit is illustrated in schematic form, in which the various components are shown in the conditions in which they will exist just prior to the start of a vending cycle.

As here shown, relays 111 and 112 are of the latching type in which one solenoid moves the relay contacts from what may be termed a normal position, to which they are spring urged, to an alternate position where they are mechanically held by a latch until released by a second or reset solenoid of the relay. A particularly suitable relay of this type is known to the trade as an Advance No. 604, which is made by the Advance Electric & Relay Co. of Los Angeles, California. Relays 113 and 114 are of the type in which the contacts are moved to and held in their alternate position only so long as their actuating solenoids are energized. Suitable relays of this type which may be used are Advance Nos. 1504-1 and 1501-2 for relays 114 and 113, respectively. A coin switch 116 and a coin reject control solenoid 117 are included in the coin mechanism 28 previously mentioned. The particular coin mechanism employed in this case is known as a National Slug Rejector, though other types could, of course, be used.

Electric current is supplied to the apparatus by power mains 118 and 119, to which sub-mains 118a and 119a are connected in parallel, respectively, through a line switch 120. A fuse 121 in power main 119 and second fuse 122 in sub-main 118a protect the circuit from overload. It will be seen, therefore, that whenever switch 120 is closed, the circuit to motor M is completed and the motor will run continuously. At the same time, the circuit to coin solenoid 117 is completed through the respective contact points of relays 113 and 114 and switch 107. Unless this coin solenoid is energized, any coin deposited in the machine will be refused and returned to the customer without actuating the associated coin switch 116. An indicator light W connected directly across sub-mains 118a, 119a, serves as a warning whenever these sub-mains are energized.

In order to facilitate a clearer understanding of the operation of the control system, the assumption will first be made that a sufficient quantity of beverage is contained in the supply tank to enable the dipper to pick up a full portion. Following this, the description of the operations involved where the dipper does not pick up such full amount will then be given.

12

As previously stated, a vending cycle is initiated by the deposit of a coin in slot 26 at the front of the apparatus. Since coin solenoid 117 has already been energized, coin switch 116 will be closed momentarily as the deposited coin falls past it. Closing this switch completes the circuit to the actuating solenoid of relay 114 and the movable contacts are accordingly shifted to their alternate position (i. e., downwardly in Fig. 9). At this instant, the following conditions prevail:

1. An alternate circuit for energizing the actuating solenoid of relay 114 is completed through contacts 123, 124, and switch 107 to sub-main 119a, thus holding the relay contacts in their present position even after coin switch 116 has again opened;
2. Coin control solenoid 117 is deenergized by the opening of its circuit at contacts 124, 125, of relay 114;
3. Clutch solenoid 96 is energized by completion of its circuit through contacts 126, 127 of relay 114, and a vending indicator lamp 128 connected in parallel with the solenoid is illuminated;
4. Cup dispenser 49 is energized to dispense a cup by means of the circuit completed through contacts 129, 130, of relay 114.

As previously explained, operation of pin-clutch C by solenoid 96 will not effect an immediate engagement of pin 82 with gear 78 unless one of the pin-receiving holes 81, 81a, in the web of the gear happens to be in alignment with the pin at that moment. However, when such engagement is effected, plate crank 58 will begin to rotate in the direction indicated. This will cause cam 58b to pass from under cam follower 109 of switch 107 and permit the switch to assume its alternate position to which it is urged by spring means. At the instant this occurs, the following takes place:

1. An alternate circuit for clutch solenoid 96 is completed through contacts 131, 132, of switch 107;
2. The circuit to the actuating solenoid of relay 114 is opened at contacts 132, 133, of switch 107, and the movable contacts of the relay return to their original position (i. e., the upper position in Fig. 9).
3. Continued rotation of vending crank 58 next cause cam 58b to actuate, momentarily, reset switch 108 by contact with its cam follower 110. This action will cause a circuit to be completed through switch 108 to the reset solenoid of relay 111. Since relay 111 has not previously been actuated, there is no change made in the system.
4. The next operation in chronological order is that of weighing the volume of beverage carried by dipper 34. As has been previously explained, this weighing is accomplished by the interaction of spring 103 and the weight of a dipperful of beverage whereby the position of cam plate 61 on plate crank 58 is varied accordingly. Since the assumption has here been made that the dipper is carrying and about to dispense a correct weight of beverage, cam plate 61 is pivotally depressed against spring 103 a sufficient distance to prevent its cam lobe 101 from actuating switch 105. Therefore, no further electrical change occurs in the system until the completion of the vending cycle, at which time cam 58b again engages cam follower 109 of cycle switch 107 and moves the switch contacts back to their original position. At this point therefore, the following condition exists:

1. Clutch solenoid 96 is deenergized by the opening of contacts 131, 132, of cycle switch 107, and clutch C thereupon disconnects plate crank 58 from its driving source; this action returns dipper 34 to the control of agitating plate crank 51;
2. Vending indicator light 128 is turned off;
3. Coin solenoid 117 is again energized and the machine is ready to receive another coin and to repeat the dispensing cycle.

As the supply of beverage in tank 32 becomes nearly depleted, the dipper will no longer be able to pick up a full measure. When this point is reached, provision is made to prevent further vending cycles of the apparatus by the actuation of the weight switch, as previously mentioned. It has been found in the practical application of this method that an exceptionally high degree of sensitivity is obtained. In fact, it has been found that the control is so sensitive that the loss from the dipper of a very small amount of beverage, as sometimes occurs during the dispensing cycle because of turbulence occasioned by the dispensing action itself, will cause the control system to be affected. The amount of this loss is generally quite unsubstantial. It is desirable, therefore, that the control system be so designed as to be capable of assuming an initial condition, upon the vending of a first substandard weight of beverage, which does not immediately stop further vending cycles but which will cause the apparatus to be stopped only upon a second consecutive occurrence of such vending of an underweight measure.

As an illustration, assume that the amount of beverage picked up by the dipper is less than a predetermined standard. The preliminary steps of operation are identical with those of the preceding description down to the point of the weighing operation. At this point however, since the weight is not great enough to cause a sufficient retraction of cam 61 and its cam lobe 101, switch 105 is actuated by the lobe passing under cam follower 106. This completes the circuit through contacts 134, 135, of relay 112 to the latching solenoid 136 of relay 111. The relay is accordingly moved to and latched in its alternate position and the circuit through contacts 137 and 138 is closed. The rest of the cycle of plate crank 58 is then completed as before, and when cam lobe 58b again actuates cycle switch 107, a circuit is completed through its contacts 132, 133, through the now closed contact points 137, 138, of relay 111, and thence to the latching solenoid 139 of relay 112. Relay 112 thereupon assumes its alternate position (i. e. movable contacts "down" in the diagram).

Upon actuation of the mechanism for a further cycle in which a substandard weight is again picked up by the dipper, the steps are the same as in the previous cycle through the point where cam lobe 58b actuates reset switch 108. In this case, however, since relay 111 has been set in its alternate position, closing of reset switch 108 releases the armature of relay 111 from its latched position by completing the circuit through its trip solenoid 140. Then, as plate crank 58 continues to rotate and the weighing operation again takes place, the closing of weight switch 105 this time causes the following to occur:

1. a circuit is completed through contacts 134, 141, of relay 112 to the solenoid of relay 113 causing its armature to move to its alternate position;

2. the armature is then held in this position by the completion of the circuit through contact points 142, 143, to the solenoid;
3. contact points 144, 145, are opened to break the circuit to coin solenoid 117 which is therefore not energized again even when switch 107 is moved to its original position by cam lobe 58b at the completion of the cycle;
4. an indicator light 146 in parallel with the solenoid of relay 113 is illuminated.

When cam lobe 58b returns to its original position and switch 107 is again actuated, a circuit is completed from the switch through contact points 137, 147, of relay 111 and contacts 148, 149, of relay 112 to the trip solenoid of the latter, releasing the armature to its original position.

Further vending operation of the machine is prevented since coin solenoid 117 is deenergized, although, of course, motor M continues to run and oscillate dipper 34 through its agitating cycle.

Whenever the above condition is reached, as will be indicated by the illumination of light 146, it becomes necessary for the machine to be manually reset before operation can be continued. This is accomplished by turning off switch 120, which immediately releases relay 113 permitting it to return to its normal position. After the supply of vendable liquid is replenished, the machine will again operate normally on closing switch 120. It will be understood that switch 120 is located inside the locked cabinet, and is therefore inaccessible to the public.

Where the vending of a substandard weight of beverage is followed immediately by the vending of a full measure, which can result, as explained, from temporary excessive turbulence during the first vending cycle rather than because of the depletion of the supply of beverage, the design of the control system is such that the apparatus will continue to function normally thereafter. As shown above, the first vending of a substandard weight causes relay 112 to be set in its alternate position (i. e. movable contacts "down" in Fig. 9). If, however, the next vending cycle is normal again, weight switch 105 will not be actuated and relay 113 will not be affected. Upon the completion of the cycle, therefore, cam lobe 58b, by returning switch 107 to its original position, causes the trip solenoid of relay 112 to be energized, thus returning this relay to its original condition. Accordingly, the control system is "cleared" of the effect of the previous cycle during which a substandard weight was dispensed.

Provision is made in the cup dispensing mechanism to cause the vending operation to be stopped when the supply of paper cups has been exhausted. In this instance, this is accomplished by the closing of a switch (not shown) within the cup dispensing unit 49 when the last cup of the supply has been delivered, thus completing the circuit between sub-main 119a and lead 160 and energizing the solenoid of relay 113 to cause it to move to the alternate position. Such action, of course, prevents further vending operations by deenergizing coin solenoid 117, and is independent of the other control operations. Cup dispensers incorporating this control are well known in the art, the type here employed being manufactured by the Johnson Fare Box Co., and accordingly form no part of the present invention.

75 It has been found in practice that the opera-

tion of clutch solenoid 96 may cause an undesirable amount of noise as the T-shaped head of the armature strikes the core at the end of its travel. This objection may be readily overcome, for example, by the incorporation of a bumper-bar 150, as shown in Figs. 4 and 5, against which an anvil 98a at the upper end of armature 98 may strike immediately preceding the completion of its travel. In this instance the bar is supported above the end of the armature by a pair of arms 151 pivotally secured to bracket 97, the arms being prevented from swinging below the horizontal by the abutment of flanges 151a against bracket 97. A short section of resilient material 152 such as rubber hoseing, for example, is placed on bar 150 for the anvil to strike against. As the armature reaches its upper or fully withdrawn position, it strikes the bumper-bar and its momentum is rapidly absorbed by the inertia of the bar and the resilience of hose section 152, thus deadening any undesirable noise.

In the normal operation of a machine of this type it is not unusual to encounter some spillage of beverage at the vending outlet because of the careless or premature removal by the customer of a filled cup. For this reason it is desirable to facilitate the rapid and complete flow from the dispensing nozzle into the cup. To assist in this, as well as to facilitate the cleaning of the unit, nozzle 45 is composed of a removable tip 45c in which a pair of rectangularly intersecting vanes 45d are centrally located. The lower tips of these vanes are beveled inwardly, respectively, so as to concentrate the flow of beverage and thus ensure a more even and rapid run-off. In spite of this precaution, however, some dripping is practically inevitable and quite frequently this may attract flies and other insects to the vending outlet. One rather simple means of overcoming this difficulty is to place an exhaust fan 153 on motor M and surround it by a duct 154. In this manner a current of air is caused to be drawn into the enclosing cabinet 20 through ventilating louvres 24 and to be discharged through cup access 25. The current of air thus created about the discharge nozzle 45 is usually sufficient to discourage any congregation of insects. If desired, indicator lamp W may be a sterilizing lamp which is placed adjacent the nozzle, thus affording further sanitary protection for the unit.

In order to prevent the beverage from running out the inner end of the rearwardly extending shank of nozzle 45 and thence down along the outside of the nozzle and the inner wall of panel 47, an internally formed bead 45e may be provided in the nozzle shank, as shown in Fig. 8. It should be pointed out, however, that the inner diameter of nozzle 45 is made sufficiently large at this point to ensure that the bead does not contact the outer surface of elbow 42, for the reasons hereinbefore described. In addition to incorporating a bead to prevent the objection to drainage above mentioned, the nozzle aperture 46 may be so designed as to cause the inwardly projecting shank of the nozzle to slope downwardly slightly toward tank 32 and thus cause any remaining beverage to drip back into the tank itself.

All parts of the apparatus coming in contact with the beverage to be dispensed should most desirably be made of a silver plated base metal, stainless steel or other material suitably resistant to corrosion and discoloration from the acids present in fruit juices or other beverages. Most of such parts are shown in Fig. 8 and include the refrigerated compartment, the beverage supply

tank, the dipper, its associated discharge nozzle, and the dipper supporting and actuating shaft and shaft-housing assembly.

What is claimed is:

1. Liquid dispensing apparatus comprising, in combination, a supply tank, a dipper device mounted to swing within said tank, power means, a driving connection between said power means and said dipper device actuatable to swing the latter into dispensing position, and means adapted and arranged, when the quantity of liquid contained in the dipper as it approaches the dispensing position is sufficiently less than a predetermined normal, to act upon said driving connection and thereby limit the extent to which it can continue dispensing operations.
2. Liquid dispensing apparatus as defined in claim 1, in which said means operable to limit the dispensing operability of said driving connection includes a device responsive to the weight of liquid contained in said dipper device.
3. In automatic liquid vending apparatus of the class described, the combination of a liquid supply tank, a measuring member for removing a quantity of liquid from said tank and elevating it to a dispensing position, driving means for actuating said measuring member, said means including a device responsive to the weight of liquid contained in said measuring member during elevation thereof above the level of liquid in the tank, and control mechanism actuatable by said device upon occurrence of a predetermined weight deficiency, to render said driving means ineffective.
4. Automatic liquid dispensing apparatus including a supply tank, a movable dipper for dispensing a portion of liquid from said tank, a power driven member, and transmission means including a clutch and actuating means therefor normally operable to connect and disconnect said dipper to and from said driven member, at the beginning and end respectively of a dispensing cycle, said transmission means further including a weighing device responsive to the weight of liquid contained in the dipper during such a dispensing cycle of the apparatus and arranged, upon occurrence of a predetermined weight deficiency, to render the clutch actuating means ineffective to connect said dipper to said driven member to initiate a subsequent dispensing cycle.
5. In automatic liquid dispensing apparatus, the combination of a liquid supply tank, a dipper pivotally depending thereinto, power means actuatable upon demand to swing said dipper upwardly into position to dispense a measured quantity of said liquid, driving means operatively connecting said dipper to said power means and including a pivoted lever whose angular position is variable in accordance with the weight of liquid contained in said dipper, and means actuatable by said lever upon occurrence of a predetermined weight deficiency, to prevent subsequent dispensing operation of the apparatus.
6. Automatic beverage dispensing apparatus, comprising, in combination, a dipper pivotally suspended to swing about a horizontal axis upwardly out of a beverage supply into dispensing position and back again in a dispensing cycle, a source of power and power transmission means connected thereto, clutch means normally actuatable upon demand to establish a driving connection between the power means and the dipper to move the latter through only one such cycle per demand, means automatically

to disestablish said driving connection, control means responsive to the quantity of beverage contained in said dipper as it approaches its dispensing position, said control means functioning when said quantity is substantially less than a predetermined standard quantity, to prevent subsequent normal actuation of said clutch means for establishment of said driving connection.

7. Automatic dispensing apparatus as defined in claim 6, wherein said control means comprises a member included in said transmission means and movable in response to the decrease in the load on the transmission means occasioned by such quantity deficiency.

8. Automatic liquid dispensing apparatus comprising, in combination, a liquid supply tank, a dipper pivotally depending thereinto, power means, a transmission connecting said power means with said dipper, said transmission including a shiftable member, shifting means operable upon demand to move said member from a normally inactive position into an active position, whereby the dipper is caused to perform a dispensing cycle movement in which it scoops up liquid and swings to a liquid dispensing position, after which the shiftable transmission member is returned to inactive position, a pivoted balance arm also included in said transmission, the position of said arm being variable in accordance with the weight of liquid contained in said dipper, and means actuatable by said arm, when the weight of liquid contained in said dipper as it approaches said dispensing position is less than a predetermined weight, to prevent said transmission member from being shifted to its dipper-actuating position.

9. Automatic liquid dispensing apparatus as defined in claim 8, which further includes means for delaying such prevention of shifting of said transmission member into dipper-actuating position until after performance of at least one additional dispensing cycle under the weight deficiency condition.

10. Automatic beverage dispensing apparatus comprising, in combination, a dipper pivoted to swing about a horizontal axis upwardly out of a beverage supply into a dispensing position and back again, in a dispensing cycle, a source of power and power transmission means operable, upon each demand, to drive the dipper through a single dispensing cycle, said transmission including a crank mounted for rotation about a horizontal axis and having driving connection to the dipper for swinging it in the aforesaid dispensing cycle, clutch means between said crank and said source of power having a member shiftable to connect the crank to or disconnect it from the source of power, clutch operating means, and an actuating member connected to said crank and constrained to rotate therewith but capable of limited movement relative thereto between an active position and an inactive position, in the former of which it is operative to act upon said clutch operating means to render the same incapable of moving the shiftable clutch member into its connecting position, spring means urging said actuating member toward its active position; the connection between said crank and said actuating member being such that, as the dipper approaches its dispensing position, the weight of the dipper and its contents acts through such connection to overbalance the opposing urge of said spring means and render said actuating member inactive, except

when the quantity of beverage contained in the dipper is substantially less than a predetermined standard quantity.

11. Automatic beverage dispensing apparatus as defined in claim 10, in which the clutch operating means is an electrical system having a control switch adapted and arranged to be actuated by said actuating member when the latter is in its active position.
12. Automatic beverage dispensing apparatus as defined in claim 11, in which said actuating member is a balance arm pivoted at one point to said crank and having a lost motion connection thereto at another point.
13. Automatic beverage dispensing apparatus as defined in claim 12, in which said balance arm is provided with a cam surface adapted and arranged, when said balance arm is in active position, to engage and actuate said control switch.
14. Beverage dispensing apparatus as defined in claim 11, in which said electrical system includes a plurality of relays arranged to be set, step-by-step, by successive actuations of said control switch, to render said clutch operating means incapable of moving the shiftable clutch member into its connecting position, and thereby to permit at least one additional dispensing cycle to be performed following the cycle in which a quantity deficiency first occurs.
15. Beverage dispensing apparatus as defined in claim 14, in which there are three relays, the first relay being set, by the initial actuation of said control switch, in a condition to actuate the second relay at the completion of the dispensing cycle, the second relay then being set in a condition whereby the next actuation of said control switch will actuate the third relay, the actuation of said third relay rendering said clutch operating means inoperative to effect a subsequent shifting of said clutch member into its connecting position.
16. Beverage dispensing apparatus as defined in claim 15, in which the electric system further includes relay-resetting circuits and control switches therefor, and cam means rotatable with said crank and adapted to engage said switches for resetting the relays.
17. Automatic beverage dispensing apparatus as defined in claim 6, in which said control means includes coin-actuated mechanism adapted and arranged to initiate movement of said dipper through a dispensing cycle upon deposit of a coin therein and to be rendered incapable of initiating subsequent dispensing cycles upon occurrence of such quantity deficiency in a preceding cycle.
18. Automatic beverage dispensing apparatus as defined in claim 10, in which the clutch operating means is an electrical system having a control switch adapted and arranged to be actuated by said actuating member when the latter is in its active position, said electrical system also including coin-actuated mechanism adapted and arranged to initiate movement of said dipper through a dispensing cycle upon deposit of a coin therein and to be rendered incapable of initiating subsequent dispensing cycles upon occurrence of such quantity deficiency in a preceding cycle.
19. In liquid dispensing apparatus, a liquid measuring device mounted to be swung about a horizontal axis upwardly out of a liquid supply into a dispensing position for gravity discharge of its contents, and then back again, in a dispensing cycle, and means for driving said device to perform such cycle; such driving means including a crank and having an extensible driving con-

nection between said crank and said device and also having a driving stroke such as would cause elevation of said device upon rotation of said crank, if unimpeded, above said dispensing position, and stop means adapted and arranged to prevent upward movement of said device beyond said position; whereby the measuring device is caused to dwell at this stage of the dispensing cycle while the crank continues to rotate.

20. Liquid dispensing apparatus comprising a liquid supply reservoir, a dipper device including a dipper having a hollow stem and terminating in a scoop, a shaft to which said dipper is operatively connected and by which it is supported for swinging movement about a horizontal axis, a driving sprocket secured to said shaft, a chain trained around said sprocket and secured at one of its ends to a spring which constantly exerts a pull thereon, a motor, a normally idle crank shaft, a crank mounted thereon for rotation in a vertical plane, a second spring operatively connecting said crank to the other end of said chain, clutch means engageable to connect said normally idle shaft with said motor for driving said shaft and its associated crank through one complete revolution to swing said dipper up into a dispensing position and back to its original position, and means interrupting the swing of said dipper at a point where its scoop end is above the horizontal plane passing through its supporting shaft but before said crank reaches the highest point in its throw, said interruption being permitted by the stretching of said second spring as said crank passes through the upper portion of its throw.

21. Liquid dispensing apparatus as defined in claim 20 in which said interrupting means comprises a pin secured to said sprocket and an adjustable stop mounted on said apparatus against which said pin abuts when said dipper is swung up into the aforesaid dispensing position.

22. In liquid dispensing apparatus as defined in claim 1, means operable to establish said driving connection which includes a shiftable clutch member, a solenoid and a source of energy therefor operable to shift said clutch member into engagement with said driving connection, said solenoid having an armature confined for movement between fixed limits, and yieldable stop means adjacent at least one of such limits against which said armature strikes immediately preceding its arrival at such limit to retard the final movement of said armature and reduce operational noise.

23. Liquid dispensing apparatus as defined in claim 1, in which said means operable to establish said driving connection includes a shiftable clutch member, a solenoid device and a source of energy therefor, said device including a movable armature, and connecting means between said armature and said clutch member for shifting the latter into engagement with said driving connection whenever said solenoid is energized, said connecting means providing a sufficiently loose connection in the deenergized condition of said solenoid to permit an appreciable initial movement of said armature before effecting the engagement of said clutch member with said driving member when said solenoid is energized.

24. An electric solenoid, a source of power therefor, said solenoid having a movable armature, a shiftable member, and means connecting said member with said armature for shifting said member to an alternate position whenever said solenoid is energized, such connecting means being adapted and arranged to provide, in the deenergized condition of said solenoid, sufficient slack in the connection between said armature and said shiftable member to permit an initial free movement of said armature when said solenoid is energized, without effecting a shifting of said shiftable member.

25. Liquid dispensing apparatus comprising a supply tank adapted to contain a body of liquid that is to be dispensed in substantially equal predetermined quantities, a liquid measuring member mounted for movement, in a dispensing cycle, from a position in said tank to a liquid dispensing position and back into the tank, driving means operable, upon initiation, to effect such movement of the measuring member through one cycle, means for initiating said driving means, weighing means for weighing the quantity of liquid contained in the measuring member as it approaches dispensing position, and means operable by said weighing means in response to a deficiency in the quantity of liquid therein for rendering said initiating means incapable of initiating another dispensing cycle.

26. Liquid dispensing means as defined in claim 25 including additional, manually operable means, connected with the initiating means for rendering the latter again capable of initiating additional dispensing cycles.

27. Liquid dispensing means as defined in claim 25 including additional means for delaying incapacitation of the initiating means until more than one successive quantity deficient dispensing cycle has been completed.

28. Liquid dispensing apparatus comprising, in combination, a supply tank adapted to contain liquid that is to be dispensed in substantially equal predetermined quantities, a liquid measuring member mounted for movement through a dispensing cycle from a normal position within said tank upwardly into a liquid dispensing position and return, power means connectable to said measuring member for driving the same through a dispensing cycle, means for effecting said connection, and weighing means acting, when the quantity of liquid contained in said measuring member as it approaches said dispensing position is less than a predetermined normal, to disable the means for effecting the driving connection against operation to drive the measuring member through subsequent dispensing cycles.
